UNITED STATES PATENT OFFICE.

ALBERT R. PRITCHARD, OF ROCHESTER, NEW YORK.

DESIGN FOR A COFFEE OR TEA POT.

SPECIFICATION forming part of Design No. 22,793, dated September 19, 1893.

Application filed June 7, 1893. Serial No. 476,886. Term of patent 14 years.

To all whom it may concern:

Be it known that I, ALBERT R. PRITCHARD, a citizen of the United States, and a resident of the city of Rochester, in the county of Monroe, State of New York, have invented and produced a new and original Design for a Coffee or Tea Pot, of which the following is a specification, reference being had to the accompanying drawings, in which—

10 Figure 1, is a side elevation of a coffee or tea pot showing my design, and Fig. 2, is a front elevation of the same.

The essential features of my design are, first, a pot body proper ornamented about the base with a repoussé molding, having a row of lanceolate ornaments, and beneath those a row of circular repoussé ornaments; second, a faceted goose-neck spout beaded along the middle lines of the front and back thereof, 20 and, third, a cover having a base part of ogee configuration, a beaded middle part and a spheroidal upper part.

In the drawings A represents the pot body proper, which is of a slightly conical form; 25 the upper part is unornamented and has at the base a raised molding, extending completely around the pot body, of greater diameter than the adjacent plain portion thereof, upon which molding is a series of upright repoussé, lanceolate ornaments *a a*, uniform in size and configuration; and next beneath and adjacent to the row of lanceolate ornaments is a molding of greater diameter than that bearing said ornaments, upon which is a se-

ries of convex beads *b b*, uniform in size and other configuration. 35

The spout B, of the general form called "goose-neck," is attached to one side of the body A, and is formed with an expanded hexagonal base, having the facets *d d*, *e e*, *f f*, 40 which extend to the first bend of the spout *y y*, Fig. 1, and from which bend other facets *g g* and *h h* and the facets *e e* extend to the beginning of the second bend *x x* of Fig. 1, from which line the spout is gradually curved 45 outward from the pot body A, and is provided with the long lower lip *i*, and the shorter upper lip *j*. On the medial lines of the front and back of the spout are beads *k k'*.

The cover C is formed of a circular base 50 portion *m* having an ogee molding *m'* about the outer part thereof. Immediately above the base portion *m*, is a circular bead *n* of smaller diameter than the base portion *m*, above which is a spheroidal top part *o*. 55

What I claim is—

1. The design for a coffee or tea pot substantially as shown and described.
2. In the design for a coffee or tea pot, the design for a spout, substantially as shown 60 and described.
3. In the design for a coffee or tea pot, the design for the cover, substantially as shown and described.

ALBERT R. PRITCHARD.
